UNITED STATES PATENT OFFICE.

JOSEPH C. STEINER, OF ST. LOUIS, MISSOURI.

DESIGN FOR A COMBINED MOTOR-HOUSING AND GEAR-CASE.

44,775.

Specification for Design.

Patented Oct. 21, 1913.

Application filed June 16, 1913. Serial No. 774,042. Term of patent 7 years.

To all whom it may concern:

Be it known that I, JOSEPH C. STEINER, a citizen of the United States of America, residing at St. Louis, in the State of Missouri, have invented a new, original, and ornamental Design for a Combined Motor-Housing and Gear-Case, of which the following is a specification, reference being had to the accompanying drawing, forming part thereof.

The figure is a perspective view, showing my new design.

I claim:

The ornamental design for a combined motor housing and gear case, as shown.

JOSEPH C. STEINER.
